UNITED STATES PATENT OFFICE.

PETER FRAY, OF NEW YORK, N. Y., ASSIGNOR TO COLUMBIA MACHINE WORKS AND
MALLEABLE IRON CO., OF BROOKLYN, NEW YORK, A CORPORATION OF NEW
YORK.

GEAR-CASE.

No. 895,247.

Specification of Letters Patent.

Patented Aug. 4, 1908.

Application filed October 14, 1907. Serial No. 397,257.

To all whom it may concern:

Be it known that I, PETER FRAY, a citizen of the United States, residing at the borough of Brooklyn, county of Kings, city and State 5 of New York, have invented an Improvement in Gear-Cases, of which the following is a specification.

My invention relates to an improved form of gear case for general use and especially for 10 use on trolley cars and other vehicles. As heretofore employed these gear cases have been made with metal peripheries and sides, which were crushed in and buckled against the gears in certain kinds of accidents and 15 particularly when striking such an obstruction as a stone between the car tracks; the gears were thus injured and often broken and could not be turned until the cases were removed.

20 In the device of my invention, the cases are made with sheet metal band peripheries having flanged edges and wooden sides secured to the same within the flanged peripheries. The sheet metal band peripheries 25 are provided with flanges and spaced apart tongues, both of which come outside of the wooden sides, the tongues being secured thereto by bolts.

End curved members with flanges are 30 connected to and strengthen the cases and bracket members support the cases from the frame of the car or vehicle. In case of an accident, with my improved gear case, the wooden sides are broken up and fall away, 35 leaving the sheet metal periphery to spring back away from the gears leaving the same free, or else when the wooden sides are broken away, it is an easy matter to so bend the metal peripheries as to bring them out of 40 contact with the gears.

In the drawing, Figure 1 is a perspective view of the device of my improvement. Fig. 2 is a vertical transverse section on about the dotted line x, x , Fig. 1. Fig. 3 is a longitudinal section at one end of the case.

45 The sides of the case a, a' , and b, b' are in pairs placed parallel with one another and in opposition; that is to say,—the sides a, a' are in line and the sides b, b' , are also in line and 50 parallel to the sides a, a' , and these parts are of wood. They are provided with stiffening strips, preferably of metal, shown at 2 and 3 and with openings shown at 4 and 5 for the shafts of the gears.

55 The form of the gear case is generally elliptical with one end smaller than the other, the

shaft opening 5 being smaller than the shaft opening 4 on account of the sizes of the shafts therein; the periphery of the case is made in two similar parts of metal c, d , comparatively thin and light and I provide end flanges e, f , with each of which is formed end curved members e', f' . The flanges e, f , are bolted together and the curved members e', f' , conform in outline to the periphery c, d , and are 60 connected thereto by suitable bolts or rivets, preferably rivets, as there is no occasion to separate these parts, therefore the periphery c is made substantially integral with the end flanges e and curved members e' , while the periphery d is substantially made integral 65 with the end flanges f and end curved members f' .

The sides a, a' , and b, b' , are to be received between and conform in shape with the shape 70 imparted to the periphery of metal bands; the opposite edges of the periphery of curved metal bands c, d , are made alike; that is to say,—they are notched at spaced apart intervals and are overturned at the bases of 75 the notches into the series of flanges 6 and the series of intermediate tongues 7. These tongues are about twice the length of the flanges and they are perforated and both the flanges 6 and the tongues 7 come outside of 80 the sides a, a' , and b, b' and lie against the outer faces thereof.

I provide bolts 8 which pass through the openings in the tongues 7 near their free ends and through openings corresponding therewith in the wooden sides of the gear case; these bolts are shown with special plainness in Fig. 2. I have also shown and prefer to employ screws 9 which pass through the peripheries c, d , of metal down into the edges 85 of the sides a, a' , and b, b' , so that between the bolts 8 and tongues 7 and the screws 9, the said peripheries are firmly and permanently secured to the wooden sides of the gear case.

I have shown and prefer to employ the bracket members 10 and 11, the member 10 having parts at right angles to one another with one part connected to the outer surface of the case and the other member connected 90 with the frame of the machine, while the member 11 has a bracket extending out from one side of one end flange e and overturned beyond the side of the gear case so as also to be adapted to be attached to part of the 95 frame of the machine.

These cases are usually employed where

there are two gears of different sizes on juxtaposed shafts, but I do not limit myself to the position of the bracket members nor to the fact that the said gear case may be provided with a door structure 12 giving access for oiling to the gears within.

From the illustration and foregoing description, it will be apparent that my improved gear case is centrally divisible or separable between the flanges *e*, *f*, the metal peripheries *c*, *d*, and the wooden sides *a*, *b*, and *a'*, *b'*, so as to facilitate putting the case in place around the gears and their shafts.

I claim as my invention:

1. A gear case comprising wooden sides of predetermined outline, a peripheral band of sheet metal extending across between the sides and notched at intervals, and having flanges and alternate tongues extending down therefrom and means for connecting said wood and metal parts together and for supporting them from the frame of the vehicle or machine.

2. A gear case comprising wooden sides of predetermined outline, a peripheral band of sheet metal extending across between the sides and notched at intervals, and having flanges and alternate tongues extending down therefrom, bolts passing through the tongues and sides of wood and screws passing through the edges of the peripheral band to the edges of the sides of wood to hold the said parts together, means for stiffening and strengthening, and other means for support-

ing the said gear case from the frame of the vehicle or machine.

3. A gear case comprising wooden sides of predetermined outline, a peripheral band of sheet metal extending across between the sides and notched at intervals, and having flanges and alternate tongues extending down therefrom, bolts passing through the tongues and sides of wood and screws passing through the edges of the peripheral band into the edges of the sides of wood to hold the said parts together, end flanges having curved members conforming to and fixed to the peripheral band of sheet metal and the flanges bolted together and bracket members of suitable form for supporting the gear case from the frame of the vehicle or machine.

4. A divisible gear case comprising wooden sides *a*, *b*, and *a'*, *b'*, in parallel pairs in opposition and of curved outline with juxtaposed meeting edges, curved peripheral bands of metal extending around and across between the sides and with edge notches at intervals, and having flanges and alternate tongues extending down therefrom, means connecting the bands and sides at said tongues, means connecting the parts of the gear case and means for supporting the gear case from the frame of the vehicle or machine.

Signed by me this first day of October 1907.
PETER FRAY.
